COLOR LIGHT SIGNAL

James A. Peabody, Evanston, Ill., assignor to
General Railway Signal Company, Rochester,
N. Y.

Application January 24, 1924. Serial No. 688,238

3 Claims. (Cl. 177—329)

This invention relates to railway signals, and more particularly to signals of the color light type.

The problem of equipping railroads with signals which will adequately protect train movements presents itself from many different angles. One particular angle or phase of this problem manifests itself on railroads where there are many overhead structures, such as bridges, viaducts, and the like. Also, in interlocking stations where several signals must be supported vertically above each other the same difficulty is experienced, namely, the difficulty in finding enough space in a vertical line to support a multiple unit color light signal or several such signals of the present day construction, and retain a uniform distance between the lights and also not have the top lights at an extreme height above the tracks. For instance, when a multiple unit color light signal is installed in accordance with the present practice of mounting the various signal units above each other, it is found that a single signal of, say, three units takes up so much room that it is difficult to support one or more additional signals of probably the same number of units, and still have the top one give a plain indication to the enginemen, particularly when the train is close under the signal.

In the employment of multiple aspect color light signals there is always an uncertainty as to whether the signal gives an indication at all, since incandescent electric lamps are preferably used and the light of such lamps is uncertain due to the limited life of the filament, so that 35 a signal at times may not give an indication at all. For instance, since the most common indication of the signal is clear, the lamp for the clear signal unit is most apt to burn out first because it is burned more than the lamps for 40 the other indications. If the clear lamp should burn out, no indication would be given by the signal at all; and although this condition might be taken as a danger signal, it may happen that the engineer would not notice the passage of a 45 signal location, and thereby run into a block already occupied.

With the above and other considerations in mind, it is proposed in accordance with the present invention to provide a color light signal comprising, among other things, a plurality of interchangeable signal units which are suitably mounted in a horizontal plane in a manner so that a complete signal consumes very little space vertically; each of these signal units to consist 50 of a light concentrating and directing device

which emits a beam of light of the desired spread in the desired direction, this light concentrating and directing device being of a construction to concentrate a very large percentage of the light emitted from a substantially point source into 60 the beam without the employment of a reflector which would tend to give a false phantom signal. As another object of this invention it is proposed to provide suitable automatic means whereby if a lamp burns out another lamp of 65 equal or a more restrictive signal indication is illuminated. More specifically it is proposed to have the caution lamp automatically cut into an energized circuit when the clear lamp burns out and clear traffic conditions prevail, so that a 70 caution signal will be given instead of a "dark" signal.

Other objects, purposes and characteristic features of the invention will appear as the description progresses.

In describing the invention in detail reference will be made to the accompanying drawings in which:

Fig. 1 shows a front elevation of a light signal embodying the present invention, portions thereof being broken away to show the construction of the adjustable support for the signal;

Fig. 2 shows a side elevation of the signal, with one of the signal units in section on the line 2—2, Fig. 1;

Fig. 3 is a plan view of the upper arm of the adjustable signal support;

Fig. 4 is a side elevation of a signal pole carrying signals above each other on suitable brackets; and

Fig. 5 is a diagrammatic view of a portion of a railway system employing signals such as shown in Fig. 1, controlled in a manner to automatically cut in a caution lamp when the clear lamp is burned out.

Referring more particularly to Figs. 1 and 2, there has been illustrated a base B of general oblong shape having its top provided with three small openings and its bottom with three large openings. This base B has mounted thereon, in the particular construction shown, three identical signal units having internal lenses of different colors for convenience designated G, Y, and R, designating green, yellow, and red, respectively. Since these units are the same the description of one will suffice for all of them.

The unit R, shown in section in Fig. 2, comprises a casing 1 of the shape shown having a large opening in the front wall and a small opening in the top and bottom walls as shown.

- The back side of the casing 1 is closed by a door 2, supported on hinges 3 and held closed by suitable hasp fastener 4. In the large opening in the front wall is supported a lens barrel 5 by bolts 6. This lens barrel 5 is provided with lens seats on opposite ends thereof; and in the larger seat is contained the outer clear lens 8 of the stepped type, this lens 8 being held in place by a bezel ring 9 and bolts 10. This bezel ring 9 is provided with a semi-circular extension to which is fastened a sun-shade 11. In the smaller end of the lens barrel 5 is contained a smaller lens 12, which in the particular signal unit described is colored red, having its convex surface stepped, as shown.
- This smaller lens 12 is held in place by a bezel ring 13 having a downwardly extending portion to which is adjustably fastened a shelf 14. On the shelf 14 is supported a lamp receptacle 15 for adjustment in a horizontal plane. Since the shelf 14 is adjustably supported for vertical movement it is apparent that the receptacle 15 may be adjusted in any desired direction by reason of the adjustment provided.
- In the receptacle 15 is supported an incandescent lamp 16 which has a concentrated filament 17 of the convoluted type. In practice, the receptacle 15 is so adjusted with respect to the bezel ring 13 and associated lenses that the lamp will emit a beam of light in the desired direction and of the desired spread. It might be pointed out at this time, that the inner lens is of such shape that the light emitted from the point source, namely the filament 17, directs the light in a funnel shaped beam which strikes the concave surface of the outer lens 8, the outer lens 8 in turn being shaped to direct this funnel shaped beam into a more concentrated beam having the desired spread. In other words, the focus of the doublet lens combination formed by the inner and outer lenses for the particular light beam desired is at a point coincident with the filament 17. By this construction a large solid angle of the light emitted from the incandescent lamp 16 is used.
- Accurate location of the filament 17 of the lamp with respect to the lens is desirable for efficiency and adequate indication. A bayonet type socket and lamp base is preferably used, since it holds the lamp rigidly in the proper position. Incandescent lamps of ordinary commercial manufacture have their filaments located differently with respect to their shape; and while adjustment of the socket 15 may be made for each new lamp inserted to replace a burned out lamp, as may be required by the particular location of the filament of that new lamp with respect to its base, it is preferred to set a fixed adjustment of the socket 15 with respect to the lenses and make this adjustment uniform for all signal units, and then re-base the lamps of commercial manufacture in a suitable manner specifically no part of the present invention, so that any rebased lamp may be inserted in any socket and without adjustment may have its filament at the proper focal point.
- The casing 1 is constructed symmetrical, so that two casings may be mounted on top of each other, if desired, wires being brought into the top casing through openings shown in the top and bottom wall of the casings shown (see Fig. 2). Also, the casing 1 may be inverted so that the door 2 swings in the opposite direction, the lens barrel and associated parts being likewise inverted. By this construction the signal unit may be mounted so that the door swings in the desired direction.
- The signal as a whole, comprising the three

units G, Y, and R, is provided with a background 20, if required, fastened thereto by screws 21 and brackets 22. The middle bottom opening in the base B is supported directly over the top member 25 of an adjustable signal support, the bottom member 26 being disposed over the cylindrical end of a pedestal 27 or corresponding support. As shown, the top member 25 may be rotated about the bottom member by reason of the arcuate guides 28 supported in grooves about the bottom member 26. These arcuate guides are fastened to the upper member by dowel screws 29, as shown. Also, the top member 25 of this adjustable support may be tilted by reason of the bolt 30 connecting the ends of the two arms 31 and 32, and extending from the top and bottom members, respectively. It should be noted that the arm 31 is provided with an arcuate slot 35 (see Fig. 3) whereby the rotatable adjustment heretofore mentioned may be made.

The wires leading to the various signal lamps are brought in through the flexible conduit 36 connected to the end of the base B by the conduit outlet 37. The two outside bottom openings in the base B heretofore mentioned are closed by covers 38 and 39 so that the wiring is entirely concealed and not exposed to moisture, detrimental gases, and the like.

In Fig. 4 has been shown a construction in which two signals such as shown in Figs. 1 and 2 are supported on a single signal pole 40. Since these signals and supports are the same, the description of one will suffice for both. The lower member of the adjustable support, instead of being supported on pedestal 27 as shown in Figs. 1 and 2, is supported on a cylindrical extension 41 projecting from the bracket 42, this bracket 42 being secured to the signal pole 40 by two U-shaped clamp bolts 43. In this construction the wires leading into the signal casings pass through a conduit 44 leading into the cover 45 closing the lower end of a cylindrical extension 41. This construction, it will be noted, permits a number of signals of several units each to be mounted on the same signal pole above each other without consuming much space. In practice, each signal is adjusted so as to direct the light beam in the desired direction. This adjustment may be roughly accomplished by loosening the set screws 33 (see Fig. 2) and adjusting the lower member of the adjustable support to the pedestal 27; and a further and more refined adjustment may be made by rotatably swinging the upper member 25 about the lower member to an extent as limited by the slot 35 in this upper member, 120 forwardly or, rearwardly tilting of the signal being accomplished by turning of the bolt 30, which is pivotally secured in the upper member 31, and locking this bolt 30 in its newly adjusted position by the lock nut shown.

Referring more particularly to Fig. 5 there has been shown a track to which signals embodying the present invention have been applied. This track apparatus comprises rails 50 divided by insulating joints 51 into blocks in the usual manner, the block I and the adjacent ends of two other blocks H and J being shown. Each of the blocks is provided with a suitable source of energy at its exit end, which has been conventionally illustrated by the battery 52, and is provided at the entrance end with a track relay T. Since the various blocks are the same like parts of each block, will be assigned like reference characters having distinctive exponents. Each of the blocks is provided with a line relay L which is energized 150

by reason of the front contact 53 of the track relay of the block at the entrance to which it is placed and the front contact 54¹ of the track relay of the block next in advance while these 5 blocks are unoccupied.

Clear indication.—Referring more particularly to the block I, the green or clear lamp G is energized under normal traffic conditions ahead through a circuit which may be traced as follows: 10 beginning at the terminal B of a suitable source of energy which has its other terminal connected to a common return wire C, front contact 55 of the track relay T, wire 56, front contact 57 of the line relay L, wires 58 and 59, winding 15 of the check relay CR, wire 60, clear lamp G, wires 61 and 62, back to the common return wire C. The energizing current for the lamp G flowing through the check relay CR is sufficient to cause this relay to assume its energized position, 20 thereby opening its back contact 63. This check relay CR may be of any desired construction, provided that it is sensitive enough to be energized by the current flowing in the lamp G without introducing a prohibited amount of resistance in 25 the circuit.

Caution indication.—If the block J should be occupied for any reason, the track relay T¹ assumes its deenergized position, drops its front contact 54¹, and deenergizes the line relay L. 30 The deenergization of the line relay L causes its contact 57 to drop, thereby closing a circuit for the caution or yellow lamp Y which may be traced as follows: beginning at the terminal B, front contact 57 in its lower position, wires 64 and 65, 35 impedance unit 66, wire 67, caution lamp Y, wires 68 and 62, back to the common return wire C. It is thus noted that the caution lamp Y at the entrance to the block I is energized when the block J is occupied.

Danger indication.—If now the block I is occupied by a train, or is in danger for some other reason, the track relay T assumes its deenergized position for obvious reasons. This causes the contact 55 of the track relay T to assume its lower 40 position, thereby closing a circuit for the red or danger lamp R which may be traced as follows: beginning at the terminal B, contact 55 of the track relay T in its lower position, wire 70, impedance unit 71, wire 72, danger lamp R, wire 50 73, back to the common return wire C.

Caution indication under clear conditions.—Let us assume that the block I and the block J are both unoccupied and that the relays T and T¹ assume the energized position thereby completing a circuit for the clear lamp G, as heretofore traced. Let us assume now that the clear lamp burns out so that it is extinguished and the energizing current which heretofore was flowing in the check relay CR has been interrupted. 55 This causes the check relay CR to assume its deenergized position, thereby completing a circuit for the yellow lamp Y, which may be traced as follows: beginning at the terminal B, front contact 55 of the track relay T, wire 56, front contact 57 of the line relay L, wires 58 and 74, back contact 63 of the check relay CR, wire 75, front contact 76 of the line relay L, wires 77 and 65, impedance unit 66, wire 67, yellow lamp Y, wires 68 and 62, to the common return wire C. 60 It is thus noted that failure of the energizing circuit for the clear lamp G, probably because the filament of this lamp has burned out, causes the caution lamp Y to be energized instead, thus giving a caution signal and allowing the engineer 65 to proceed instead of having no signal to guide, 70 75

advise or protect him against possible danger ahead.

The impedance units 66 and 71 have an impedance approximately equal to that of the resistance of the check relay CR. These impedance units are employed so that the incandescent lamps used in the signals G, Y, and R, respectively, may be of the same candle power and current carrying capacity and may be interchanged if desired. It should be noted that not only failure of the filament of the lamp G causes the lamp Y to be energized instead, but that failure of the winding of the control relay CR, either because it is open or because it is shunted, causes energization of the caution lamp Y.

In the particular arrangement of track circuits shown the clear lamp G only has been protected against open circuits by the check relay CR by energizing the caution or lamp Y instead of clear lamp G. It should, however, be understood that the same arrangement may be applied to the caution lamp Y by providing a similar check relay in series with such caution lamp and providing a back contact which completes a circuit for the red lamp R when such caution lamp is deenergized; also, the same arrangement may be applied to the red lamp R by providing another auxiliary red lamp which is energized if the red lamp of the signal is burned out or its energizing circuit is open for some other reason, the same arrangement being applicable to lamp G and Y.

From the foregoing will be observed that the color light signal of this invention has a horizontal arrangement or disposition of the light 110 projecting units, three of these units being ordinarily used to give the common indications of clear, caution, and danger. This particular arrangement of signal units has a number of important advantages. In the first place, it makes 115 the whole signal of such form that it is more adaptable to the space requirements encountered in practice in many instances. For example, in tunnels, subways, on bridges, and under similar conditions, the clearances make it possible to 120 employ the horizontal arrangement of light units characterizing this invention, where a vertical disposition of light units, frequently employed, would be impossible. Also, all of the light units are brought down on the same plane in the line 125 of vision. On certain railroads overhead structures are frequently found. The signals themselves sometimes being supported on bridges; and under these conditions the signal of this invention provides a visibility and range for all indications of the signal that could not be obtained by a vertical disposition. The space economy 130 above mentioned is particularly accentuated in terminals and other points of congested track- 135 age where it is necessary to have two or more complete signals close together at the same point. Furthermore, the units may be arranged in different order as to color and the different signals arranged above each other as shown in Fig. 4, as 140 for instance, the red signals can be located in staggered relation to give a permissive or special aspect to the signal.

As already stated, the green or clear lamp being the one burning the greatest part of the time, perhaps ninety-five per cent of the time, 145 is the lamp which is used the most and which will be the one to burn out first. If the clear or green light should burn out under clear traffic conditions, a so-called "dark" signal is the result; and while such a "dark" signal, accord- 150

ing to the rules, signifies stop, the engineer may fail to observe the signal making it desirable to use an additional marker lamp to locate the signal. This invention provides, however, for cutting in and lighting the yellow or caution lamp whenever the green or clear lamp burns out, thereby providing a reserve indication for the green indication which not only serves the purpose of a marker light but also is more likely to assure safe control of the train. It is considered preferable to cut in the yellow or caution indication upon burning out of the green lamp, rather than cutting in a reserve lamp for the green signal, because the engineer under ordinary circumstances would observe the showing of a caution indication instead of a clear indication and would report the abnormal condition, making prompt repair more certain than if a green lamp in reserve is used. On the other hand if the signal in question is an approach signal where the yellow or caution lamp is burning almost continually it is considered preferable to have an auxiliary lamp giving the same distinctive indication when such caution lamp burns out. If desired, additional resistance may be cut in series with the yellow lamp when lighted because of failure of the green lamp, so as to give weaker caution indication and show the engineer that something is out of order; but ordinarily the engineer would be able to detect the showing of a yellow light where a green lamp should be displayed.

Although the invention has been shown applied to a color light signal it is desired to be understood that it may also be applied to position light signals, where a group of lights are used to define a bar or signal blade the position of which determines the signal indication.

Having thus shown one specific embodiment of the present invention and the manner in which it may be applied to one particular type

of trackway apparatus and associated relays, it is desired to be understood that various changes, modifications, and alterations may be made to adapt the invention to any other system and the various conditions encountered in practice without departing from the spirit of the invention or the idea of means underlying the same.

What is desired to be secured by Letters Patent of the United States is:—

1. In a light signal, a hollow base member having a plurality of flat portions on one face and in the same plane and with an opening in each portion forming a means of communicating with the hollow of the body, a plurality of identical light projecting units each having a flat base portion parallel to its optical axis and provided with an opening in said base portion, said hollow member and said units also including means for interchangeably mounting the units on the hollow base member.

2. In a light signal, in combination, a hollow flat base member having a plurality of openings in its upper face, a plurality of identical light projecting units each having a flat base provided with an opening therein, and means to connect the light units to the base member and with the unit openings over the openings in the upper face of the base member.

3. In a light signal, in combination, a hollow flat base member having a plurality of openings in its upper face, a plurality of identical light projecting units each having a flat base, means to connect the light units to the base member and over the openings in the upper face thereof, an opening in the base of each light unit registering, when the unit is in place, with the corresponding opening in the upper face of the base member, and a terminal box connectable to the base member and communicating with the hollow of the base member.
